I claim the ornamental design for a drum key holster and ring, as shown and described.

DESCRIPTION

FIG. 1 is a front and left hand side perspective view of my design for a drum key holster and ring;

FIG. 2 is a front right hand side perspective view of a drum key shown in FIG. 1;

FIG. 3 is a front left hand side exploded, unassembled view of my design for a drum key holster and ring;

FIG. 4 is a front view of my design for a drum key holster and ring;

FIG. 5 is a back view thereof;

FIG. 6 is a right side view thereof;

FIG. 7 is a left side view thereof;

FIG. 8 is a bottom view thereof; and,

FIG. 9 is a top view thereof.
